UNITED STATES PATENT OFFICE.

BLANCHE S. NICHOLS, OF NEW BRITAIN, CONNECTICUT.

CUFF.

1,161,511.

Specification of Letters Patent. Patented Nov. 23, 1915.

Application filed February 3, 1915. Serial No. 5,823.

To all whom it may concern:

Be it known that I, BLANCHE S. NICHOLS, a citizen of the United States, residing at the city of New Britain, county of Hartford, 5 in the State of Connecticut, have invented certain new and useful Improvements in Cuffs, of which the following is a full, clear, and exact description.

My invention relates to an improved so-called soft cuff.

The object of the invention is to provide certain structural improvements whereby the cuff is caused to hold its intended shape.

The invention is also applicable to reversible soft cuffs.

In the drawings, Figure 1 is a perspective view of the cuff as it would appear in use, parts of the cuff being broken away. Fig. 2 is a plan view of the cuff open and with the 20 flap extended and on a slightly reduced scale, parts of the cuff being broken away. Fig. 3 is a section on the plane of the line 3—3 relatively enlarged. Fig. 4 is a section on the same plane with the forward 25 part or flap of the cuff folded back as in use.

The cuff comprises what I may term the main body or wrist portion 1 and the foldable portion or flap 2. These two parts are 30 provided with the usual buttonholes. It is well known that in laundering soft cuffs practically no starch is used, with the result that in service such cuffs very quickly became wrinkled, particularly that part of 35 the cuff which lies adjacent to the upper side of the wrist. If a cuff becomes wrinkled in this locality it presents a noticeably unsightly appearance. To prevent this I have provided an improved flexible reinforcing 40 means in this locality which lends that degree of stiffness to the cuff necessary to preserve its appearance without being uncomfortable.

In the drawings I have shown the cuff 45 partly broken away so as to expose the reinforcing means, which in this specific instance comprises, by preference, two slightly spaced members 3 and 4 of appropriate flexible reinforcing material, preferably 50 hair cloth in which the hairs are arranged so as to run parallel with the arm or wrist of the wearer. The ends of each of the reinforcing pieces 3 and 4 are suitably formed, or covered, so as to hold the individual hairs 55 from independent endwise movement, thus preventing one or more of the hair ends

from penetrating the material of the cuff to the discomfort of the wearer. By providing two slightly spaced reinforcing members 3 and 4 near the middle of the cuff, instead 60 of one continuous member of substantially the area of the aforesaid two pieces, the cuff very readily conforms to the wrist of the wearer when applied, since said cuff may readily bend along the line of separation 65 between said two members. The reinforcing means is preferably located between the plies of the main body 1 rather than between the plies of the flap 2, because, in order to secure the best results, it is desirable that the 70 outer fold of the cuff should be relatively soft and unreinforced throughout, save as it is supported and held in shape by the underlying reinforced main body portion 1. It follows that since the underlying main 75 body portion cannot readily become wrinkled, but tends to remain flat, the outer fold will preserve an attractive appearance. Again, by placing the reinforcement within the main body 1 of the cuff, its location 80 therein determines definitely the width of the fold and the line upon which the cuff is bent to conform most comfortably to the shape of the wrist. These cuffs may be attached to the shirt sleeve in any desired way, 85 said shirt sleeve being indicated in dotted outline at 5.

While of course any number of reinforcing members may be employed, I have found that the best results are obtained by employing two relatively small pieces located in the manner above described. The reinforcing pieces may be fastened in place in any desired manner, as for example, by 90 stitches. I have also ascertained that the 95 greatest comfort is assured by leaving those parts of the cuff where the buttonholes are provided unreinforced by special reinforcing members.

While the reinforcing means is always 100 flexible in every direction, it is relatively less yielding in that direction which would cause the cuff to become wrinkled than it is in the direction in which it is bent in the act of applying the cuff to the wrist. In this 105 latter direction it always bends freely so that its presence cannot be detected by any unsightly bulging of the cuff when being worn.

What I claim is:

1. A cuff comprising a main body portion 110 extended into a second portion arranged to

be folded back upon the main body portion, a yielding reinforcing means permanently united with the cuff, said reinforcing means being relatively less yielding in one direction than the other, said reinforcing means being located adjacent the middle portion only of the cuff.

2. A cuff comprising a main body portion extended into a second portion arranged to be folded back upon the main body portion, a yielding reinforcing means permanently united with the cuff, said reinforcing means being relatively less yielding in one direction than the other, and comprising two separate members arranged with one edge of one member close to one edge of the other

member and located to the middle portion only of the cuff.

3. A cuff comprising a main body portion extended into a second portion constituting a flap arranged to be folded back upon the main body portion, a yielding reinforcing means permanently united with the main body portion only and arranged to prevent the cuff from becoming wrinkled, said reinforcing means being located only near the middle of the body portion, the ends of said body portion being relatively unreinforced.

BLANCHE S. NICHOLS.
